SUPPORTING ELEMENT FOR ELECTRICAL DEVICES

Filed Aug. 7, 1929

UNITED STATES PATENT OFFICE

FRANK H. HUBBARD, OF WAUWATOSA, WISCONSIN, ASSIGNOR TO CUTLER-HAMMER, INC., OF MILWAUKEE, WISCONSIN, A CORPORATION OF DELAWARE

SUPPORTING ELEMENT FOR ELECTRICAL DEVICES

Application filed August 7, 1929. Serial No. 384,157.

This invention relates to improvements in supporting elements for electrical devices. Where electric switches or plug receptacles are mounted in the ordinary wall outlet boxes it is desirable to provide means for insuring substantially flush alinement of the former with respect to the finished surface of the wall even though the outlet boxes may be set crooked in the wall. Also, it is extremely desirable that the device be firmly attached to its outlet box without subjecting the wall surface to an undue pressure and the present invention has among its objects to provide simple and efficient supporting elements for accomplishing the foregoing and other desirable results.

Another object is to provide a one-piece supporting element having a wall engaging part and an attaching lug which may be bent relative to the wall engaging part to permit such lug to be clamped against an improperly set outlet box without impairing the alining function of the support.

Another and more specific object is to provide an element of the aforementioned character wherein the attaching lug is bendable as aforesaid after the element is engaged with the wall and without damage to the wall surface.

Other objects and advantages of the invention will hereinafter appear.

The accompanying drawings illustrate certain embodiments of the invention which will now be described, it being understood that the invention is susceptible of embodiment in other forms without departing from the scope of the appended claims.

In the drawings, Figure 1 is an enlarged plan view of one form of supporting element embodying the invention.

Fig. 2 is a sectional view on the line 2—2 of Fig. 1.

Fig. 3 is a sectional view of an outlet box fitted in a wall and having an electric switch supported therein by elements similar to those shown in Figs. 1 and 2.

Fig. 4 is a fragmentary plan view of the arrangement shown in Fig. 3,—a portion of the flush plate or cover being broken away for purposes of illustration.

Fig. 5 is a plan view of a modified form of supporting element constructed in accordance with the invention, and

Figs. 6 and 7 are similar views of further modifications.

Referring first to Figs. 1 to 4, the numeral 15 designates a flat base portion of the supporting element. Base portion 15 may be of any desired contour, and as shown in Fig. 4 the same is adapted to fit within a correspondingly shaped recess 16 in the insulating casing 17 of a switch, the actuating element of which is shown at 18 in Fig. 3. The recess 16 is further countersunk or otherwise formed to accommodate the substantially elliptical depression 19 in base portion 15. Depression 19 is provided with a pair of tapped openings 20 and 21, the opening 21 being adapted to receive the shank 22 of a screw which penetrates the insulating casing 17 to rigidly secure base portion 15 thereto. Opening 20 is adapted to receive the shank of a screw 23 for securing one end of the flush plate or cover 24 in position.

Slightly offset upwardly, by means of the bent portion 25, and extending outwardly in a plane parallel to the plane of base portion 15 is an attaching lug 26 integral with said base portion,—said lug preferably having a substantially elliptical perforation 27 with a beveled edge 28 to receive the beveled head 29 of a screw for clamping lug 26 against the usual lug 30 on the outlet box 31.

Also integral with base portion 15 and offset upwardly therefrom to lie in the same plane as the lug 26 is a wall or plaster engaging part designated in general by the numeral 32. Said part 32 comprises arms 33 and 34 and a span 35 integral therewith, said arms 33, 34 and span 35 being separated or spaced from the lug 26 by means of the connecting slots 36, 37 and 38, respectively.

Referring more particularly to Figs. 3 and 4, the numerals 39 and 40 designate the wall boarding to which the outlet box 31 is secured by lugs 41 and screws 42 in the usual manner. As shown the outlet box 31 is set crooked in the wall, so that the lug 30 bears an inwardly offset relation to the outer surface 44 of the plaster 43, whereas the lug 30^a is flush

with such surface, although of course it might be offset inwardly to the same or a different degree. By merely bending inwardly the attaching lug 26 to the required degree, as illustrated at the upper end of Fig. 3, the aforementioned offsetting or misalignment of lug 30 of the outlet box may be compensated for; it being noted that such bending of lug 26 may be effected without distortion or misalignment of the plaster engaging part 32 with respect to the top surface 45 (Fig. 3) of the switch. By the arrangement described the necessity for employment of the usual washers or spacers (not shown) between the lugs 26 and 30 is avoided. Moreover, by providing for flexure of the lug 26 with respect to base portion 15 and plaster engaging part 32 said lug 26 may be brought into proper engaging relation with lug 30 (when the latter is offset or misaligned as aforescribed) without causing the portion 32 to engage the plaster with such a degree of force as to crush the latter.

Such bending of lug 26 may be effected by inserting a screw driver or the like within perforation 27 and then prying said lug downwardly, as will be obvious. On the other hand, if a sufficiently thin metal stock is employed in constructing the element aforescribed, the lug 26 may be bent downwardly by merely applying manual or thumb pressure. Such manual bending may be facilitated by providing lug 26 with a weakening perforation, such as that indicated at 26^a in Fig. 4. As will be obvious, the arrangement may be such that the lugs 26 will be more readily bendable than the plaster engaging portions 32, so that upon driving home of the screws 29 lugs 26 will be brought into proper engaging relation with lugs 30, 30^a whereas the plaster engaging portions will function to maintain flush alignment of the switch or other electrical device with respect to the plaster surface.

The element shown in Fig. 5 is identical in many respects with that shown in Figs. 1 to 4, and corresponding parts have been given like numerals of reference. In this construction, however, the supporting lug 26^b is only indirectly connected with base portion 15; that is to say, through the medium of the plaster engaging portion from which it is separated on three sides by the connecting slots 36, 37 and 38. Lug 26^b may be bent in the manner aforescribed to provide for proper securing thereof to the outlet box, without bending of the plaster engaging part 32 with respect to base portion 15.

Fig. 6 shows an element quite like that of Fig. 5, but in which the slots 36^a, 37^a and 38^a are preferably made slightly narrower to provide for increased resistance to bending of the arms 33^a, 34^a; and said slots 36^a, 37^a converge or approach each other to provide for decreased resistance to bending of the lug

26^c. Also in this form the base portion 15^a is provided with a pair of spaced tapped openings 21^a to provide for attachment thereof to an electrical device, and an intermediate tapped opening 20^a to receive the shank of a 70 cover plate attaching screw, such as shown at 23 in Fig. 3. Thus the lug 26^c in Fig. 6 will readily bend under the force incident to tightening of the screw 29 to compensate for possible misalignment of the lug 30 of the outlet box (Fig. 3) without causing distortion or bending of the plaster engaging part 32.

Fig. 7 illustrates an element of the character shown in Fig. 1, but having relatively narrow converging or connecting slots 36^b, 37^b and 38^b similar to the slots shown in Fig. 6, but in reversed relation as compared with the latter. In this arrangement the lug 26^d is likewise more readily bendable than the plaster engaging portion 32, and the element 85 functions in the novel manner aforescribed. The base portion 15^b of Fig. 7 may be of any desired form, but as shown the same is provided with a pair of relatively widely spaced tapped openings 21^b for attachment of the element to an electrical device of special form, and an integral lug 15^c having a tapped opening 20^b for reception of the cover plate attaching screw is likewise provided.

It is of course to be understood that supporting elements of the several forms herein disclosed might be formed integrally with the numerous types of supporting strips and straps with which switches and plug receptacles and other electrical devices are commonly provided.

What I claim as new and desire to secure by Letters Patent is:—

1. The combination with an electrical device to be supported in a wall outlet box, of supporting means for said device attached thereto and having projecting lugs to be attached to the outlet box and projecting wall engaging parts to position said device relative to the wall, said lugs and wall engaging parts 105 being coordinated to occupy the same plane and said lugs being bendable out of the plane of said parts to approach the outlet box.

2. The combination with an electrical device to be supported in a wall outlet box, of supporting means for said device attached thereto and having projecting wall engaging parts and lugs for attachment to the outlet box, said parts and lugs being grouped and those of each group being formed of a single piece of sheet metal cut to permit bending of the lugs relative to the wall engaging parts.

3. The combination with an electrical device to be supported in a wall outlet box, of supporting means for said device attached thereto and having projecting bendable lugs for attachment to the outlet box and projecting wall engaging parts to aline said device with the wall and to prevent its displacement 130

by bending of said lugs to approach the outlet box.

4. The combination with an electrical device to be supported in a wall outlet box, of supporting means for said device attached thereto and having projecting wall engaging parts and lugs for attachment to the outlet box, said parts and lugs being grouped and those of each group comprising a sheet metal 10 stamping formed to permit the attaching lugs to be bent relative to the wall engaging parts and to render the latter substantially non-yielding to bending pressure exerted on said lugs.

15 5. A sheet metal supporting element of the character set forth having a wall engaging part and an attaching lug bendable independently of and relative to said part.

6. A unitary sheet metal supporting element 20 for an electrical device, which comprises a base portion, a projecting attaching lug and a projecting wall engaging part, said lug being bendable relative to said part and the latter being substantially non-yielding to 25 bending pressure exerted on said lug.

7. A unitary sheet metal supporting element 30 for an electrical device, which comprises a base portion, a projecting wall engaging part and an attaching lug within the contour of said wall engaging part, said element being cut to permit said lug to be bent relative to said wall engaging part.

In witness whereof, I have hereunto subscribed my name.

35 FRANK H. HUBBARD.
